DESIGN FOR A COLORIMETER

Edward F. Flint, Rochester, N. Y., assignor to
Bausch & Lomb Optical Company, Rochester,
N. Y., a corporation of New York

Application December 2, 1939, Serial No. 88,641

Term of patent 7 years

To all whom it may concern:

Be it known that I, Edward F. Flint, a citizen
of the United States, and a resident of Rochester,
county of Monroe, and State of New York, have
invented a new, original, and ornamental Design
for a Colorimeter, of which the following is a
specification, reference being had to the accom-
panying drawing, forming a part thereof.

Fig. 1 is a front elevation of a colorimeter em-
bodying my new design.

Fig. 2 is a side elevation thereof.

Fig. 3 is a rear elevation thereof.

Fig. 4 is a top plan view thereof.

I claim:

The ornamental design for a colorimeter, sub-
stantially as shown.

EDWARD F. FLINT.
